DESIGN FOR A CAKE OF SOAP

Jean E. Vivaudou and Henry G. Lubin,
New York, N. Y.

Application May 11, 1942, Serial No. 106,862

Term of patent 7 years

To all whom it may concern:

Be it known that we, Jean E. Vivaudou and Henry G. Lubin, a subject of the King of Great Britain and a citizen of the United States, respectively, both residing at New York city, in the county of New York and State of New York, have invented a new, original, and ornamental Design for a Cake of Soap, of which the following is a specification, reference being had to the accompanying drawing, forming a part thereof.

In the drawing:

Fig. 1 is a top plan view of a cake of soap, showing our new design;

Fig. 2 is a bottom plan view; and

Fig. 3 is a side elevational view of the same.

We claim:

The ornamental design for a cake of soap, as shown.

JEAN E. VIVAUDOU.
HENRY G. LUBIN.
